UNITED STATES PATENT OFFICE.

OTTO H. MOHR, OF SAN FRANCISCO, CALIFORNIA, ASSIGNOR TO HYDRO-SUCTION
CLEANER CO., A CORPORATION OF CALIFORNIA.

VACUUM CLEANING APPARATUS.

1,011,989.

Specification of Letters Patent. Patented Dec. 19, 1911.

Application filed August 31, 1910. Serial No. 579,894.

To all whom it may concern:

Be it known that I, OTTO H. MOHR, a citizen of the United States, and a resident of the city and county of San Francisco and State of California, have invented new and useful Improvements in Vacuum Cleaning Apparatus, of which the following is a specification.

The invention relates to vacuum cleaning apparatus and particularly to a cleaning tool provided with a dirt receptacle for collecting and retaining the dirt and dust.

In the operation of vacuum cleaners in which the suction device is removed somewhat from the cleaning tool, much of the energy of the suction is lost in transporting the dust and dirt through the long length of hose and in the friction of the dust and dirt as it passes through the hose.

In the present invention I contemplate separating the material carried by the air current, from the air at a point on or in close relation to the cleaning tool, so that the material will be carried only a short

distance by the air.

In carrying out my invention I preferably place a dirt receptacle on an extension of the cleaning tool constituting a handle and connect such receptacle to the handle in such a manner that all of the dirt laden air passing through the cleaning tool is diverted into the dirt receptacle. In the dirt receptacle between the inlet and the outlet I arrange a screen or arresting means so that the dirt and dust is deposited in the receptacle and the air passes through. The receptacle is so arranged that it can be readily removed when it becomes full, so that the dirt may be emptied.

The object of the invention is to provide a dirt receptacle on the cleaning tool adapted to retain all of the dirt raised, so that the loss of energy due to the carrying of the dirt through the long conductor to the suction means is obviated.

With this and other objects in view, as will more fully hereinafter appear, the invention consists of certain novel features of construction and arrangement of parts hereinafter fully described, illustrated in the accompanying drawings and particularly pointed out in the appended claims, it being understood that various changes in the form, proportion, size and minor details of

the structure may be made without departing from the spirit or sacrificing any of the advantages of the invention. 55

Referring to the drawings, Figure 1 is a view of a cleaning tool with the dirt receptacle attached thereto. Fig. 2 is a section 60 through the dirt receptacle and the connection for attaching the same to the air line.

The cleaning tool, as herein represented, comprises the usual head having therein the inlet 2, and the sections 9 and 12 which may be tubular and are shown as being connected with the usual flexible or other conduit leading to the suction means. The sections 9 and 12 constitute a handle for moving the tool about a floor, or other surface to be 70 cleansed. The dirt receptacle 15 is attached to the air line, between the suction means and the inlet 2 of the cleaning tool in close relation to the cleaning tool. The receptacle is preferably located on the handle. The 75 cleaning tool or the handle is connected to any suitable suction means, not shown in the drawings, by a single conductor through which the air is drawn. The material removed from the floor or other surface by 80 the air is, therefore, carried only a short distance and deposited in the dirt receptacle and the energy of the suction is not absorbed by carrying the material through the conductor. 85

It is evident that when a long conductor connects the cleaning tool with the suction much of the energy of the suction is consumed in carrying the material through the conductor and in the friction of the material in the conductor. By the use of the present invention, however, all of the coarser material is removed from the conductor at a point near the cleaning tool, thereby greatly increasing the efficiency of 95 the cleaning apparatus. 90

The coupling 4 for connecting the dirt receptacle with the air line consists of the elbow 5 having two passages 6-7 extending therethrough. The passages are separated from each other by the central rib 8 so that the air is constrained to pass through the dirt receptacle. The passage 6 is connected to the conductor 9 which extends to the head of the cleaning tool and passage 7 connects with the conductor 12 which is connected with the suction device. The dirt laden air therefore enters the dirt re- 100 105

ceptacle through passage 6 and passes out through passage 7 when the dirt has been removed. A circular plate 13 having a depending flange 14 is provided on the lower end of the elbow and preferably integral therewith. The dirt receptacle 15 is preferably cylindrical in shape and is provided with a screw thread at its open end to engage a similar thread on the depending flange 14. A washer or packing ring 16 is generally provided between the receptacle 15 and the plate 13 to form an air tight joint. A tube 17 extending into the receptacle is secured in passage 6 for conveying the dirt carrying air to the lower part of the receptacle. The outlet from the receptacle through the passage 7 is covered by a screen 18 to prevent the dirt from passing out of the chamber. The screen 18 is made of larger superficial area than the area of the outlet to increase the efficiency of its action. In the drawings I have shown the screen 18 to be cylindrical in shape, closed at bottom and top except at the offset portion where it is attached to the ferrule 19 which fits the passage 7. It is to be understood, however, that the screen could be made in other forms and arranged in the receptacle between the inlet and the outlet. The receptacle 15 is preferably made of glass, so that the operator can observe the amount of dirt therein, and remove said dirt when necessary. To prevent injury to the receptacle by coming in contact with the floor when the tool is dropped, or by other circumstances, I provide a guard or bumper rings 21 of soft rubber or felt, encircling the receptacle and lying between it and the conductor. When an amount of dirt has been collected in the receptacle, it is unscrewed from the cap 13, emptied, and screwed back into position. In the preferred construction, as shown in Fig. 1 of the drawings, the receptacle is so located that it depends below the handle of the tool during the cleaning operation and assumes a more or less inclined position, so that the dirt tends to gravitate to the lowest part of the receptacle and collect below the screen 18 and inlet pipe 17. The screen 18, is of sufficiently fine mesh to arrest practically all of the dust or dirt during the passage of air through the apparatus, and the receptacle is of course removed and the dirt emptied before it rises high enough in the

receptacle to interfere with the free passage of the air.

I claim:

1. In a vacuum cleaning apparatus, a cleaning tool for attachment to a suction line, a dirt receptacle mounted externally on the cleaning tool, means for diverting the air through the receptacle and dirt arresting means in the receptacle between the inlet and outlet. 65

2. In a vacuum cleaning apparatus, a cleaning tool for attachment to a suction line, comprising a head through which the air is drawn and a handle, a dirt receptacle on the handle, a connection for diverting the air through the receptacle and dirt arresting means in said receptacle between the inlet and outlet. 70

3. In a vacuum cleaning apparatus, a portable cleaning tool for attachment to a suction line, comprising a head through which the air is drawn and an extension adapted to serve as a handle, a dirt receptacle mounted on said extension in close proximity to said head, means for diverting the air through the receptacle, and dirt arresting means in said receptacle. 75

4. In a vacuum cleaning apparatus, a cleaning tool to be connected with a suction line, a dirt receptacle mounted externally on the tool and arranged to depend downwardly therefrom when the tool occupies its normal position during the cleaning operation, means connecting the tool and receptacle arranged to divert the air through the receptacle, and dust-arresting means in the receptacle between the inlet and outlet. 85

5. In a vacuum cleaning apparatus, a cleaning tool to be connected with a suction line, a dirt receptacle mounted externally on the tool and arranged to depend downwardly therefrom when the tool occupies its normal position during the cleaning operation, an inlet connection between the tool and receptacle and an outlet connection between the receptacle and air line, said connections entering the upper part of the receptacle, and arranged to divert the air therethrough, and dust-arresting means in the receptacle between the inlet and outlet. 95 100 105
